EDGE GRINDING APPARATUS

Raoul J. Louviaux, Toledo, Ohio, assignor to Libbey-Owens-Ford Glass Company, Toledo, Ohio, a corporation of Ohio

Application October 30, 1931, Serial No. 571,996

4 Claims. (Cl. 51—33)

The present invention relates broadly to improvements in grinding machines and more particularly to a machine or apparatus for grinding the corners of sheets of glass and the like.

An important object of this invention is the provision of a grinding machine of the character above described which will operate not only to round the corners of the glass sheet but which will at the same time bevel or finish the said corners whereby uniformly rounded corners with well finished surfaces are secured.

Another object of the invention is the provision of such a grinding machine of simple, inexpensive construction, which will round the corners of the glass sheets rapidly, accurately and economically and with a minimum effort and attention on the part of the operator.

A further object of the invention is the provision of such a grinding machine operable for rounding the corners of glass sheets, the edges of which are disposed to form either a 90° angle or an angle either greater or less than a 90° angle.

Still another object of the invention is the provision of such a grinding machine including an abrading element, together with means for adjusting said element to compensate for the wear thereupon.

Other objects and advantages of the invention will become more apparent during the course of the following description when taken in connection with the accompanying drawings.

In the drawings forming a part of this application and wherein like numerals are employed to designate like parts throughout the same,

Fig. 1 is a side elevation of a grinding machine constructed in accordance with the present invention,

Fig. 2 is a plan view thereof,

Fig. 3 is an elevation of the driving means for the abrading element,

Figs. 4, 5 and 6 are diagrammatic views showing the swinging movement of the abrading element, and

Figs. 7 and 8 are views somewhat similar to Figs. 4 to 6 but showing the grinding of glass sheets, the edges of which are disposed to form an angle either greater or less than a 90° angle.

Referring now to the drawings, and particularly with reference first to Figs. 1 to 3, the grinding machine herein provided comprises a supporting framework designated in its entirety by the numeral 10 and which may be constructed of suitable structural elements including the

four vertically disposed corner supports or legs 11, 12, 13 and 14 connected together at one or a plurality of points throughout their vertical extent by the horizontal cross pieces 15, 16, 17 and 18. The cross pieces 16 project beyond leg 12 and secured at their outer ends to a vertical leg 19. Disposed opposite leg 11 is a vertical leg 20 connected thereto by one or more cross pieces 21 and also connected with leg 19 by one or more cross pieces 22.

Supported by the legs 19 and 20 of the framework 10 is a substantially L-shaped bracket 23 comprising a horizontal bottom portion 24 provided along its outer longitudinal edge with an upstanding vertical portion 25. Carried by the L-shaped bracket 23 are a plurality of horizontally aligned rollers 26 which are adapted to constitute a supporting runway for the glass sheets 27, the corners of which are adapted to be rounded. Each of the rollers 26 is provided with a plurality of grooves 28 within which the lower edges of the glass sheets are received when the said sheets are stood in a vertical position. Each roller 26 is also freely mounted upon a transverse pin 29 which extends through a vertically disposed slot 30 formed in the upstanding side portion 25 of bracket 23 and has threaded thereupon outwardly thereof a nut 31. With such a construction, it will be seen that the sheet supporting rollers 26 can be readily raised or lowered as desired upon loosening the nuts 31.

Also carried by the leg 28 above the L-shaped bracket 23 is a forwardly projecting horizontal bar 32 upon which is slidably mounted the sheet retaining member 33, said member being adapted to engage the forward vertical edges of the glass sheets 27 so as to maintain the said sheets in a vertical position during the grinding operation. In order to more effectively retain the sheets in a vertical position, the member 33 is preferably formed with a plurality of grooves or the like 34 within which the front vertical edges of the glass sheets are received.

Secured to the legs 11 and 20 of the supporting framework 10 are the horizontally aligned bearing brackets 35 and 36 respectively within which is rotatably mounted a horizontal shaft 37. Keyed to this shaft 37 between the bearing brackets 35 and 36 is a swinging carriage 38 provided with a rectangular opening 39 extending laterally therethrough.

Carried by the carriage 38 and arranged transversely thereof is a relatively long bearing sleeve 40, said sleeve being received through the lateral opening 39 and being formed intermediate its

50

55

ends with a substantially square portion 41 slideable within the said opening. Journaled within the sleeve 40 is a shaft 42, said shaft projecting at opposite ends beyond the said sleeve and carrying at one end the abrading element 43 here shown as being in the form of a disk or wheel provided with a plurality of grooves 44 in the periphery thereof and which grooves are adapted to be in alignment with the grooves 28 in the sheet supporting rollers 26.

Supported upon a horizontal platform 45 carried by framework 10 is an electric motor 46 driving through suitable reduction gearing located in casing 47, a shaft 48. Fixed to the outer end of shaft 48 is a crank 49 carrying at its outer end a crank pin 50 upon which is pivoted one end of a crank arm 51, the opposite end thereof being pivotally connected with the swinging carriage 38 as at 52. Inasmuch as the shaft 37 is rotatably mounted within bearing brackets 35 and 36, and the carriage 38 is keyed to shaft 37, it will be readily understood that, upon operation of motor 46 to drive shaft 48, the crank 49 will be rotated so as to reciprocate the crank arm 51 and thereby cause the carriage 38 and consequently the abrading wheel 43 to be swung back and forth through a vertical arc about the axis of shaft 37. In other words, the abrading wheel is oscillated through an arc in a plane parallel with the plane of the glass sheets 27. The glass sheets are adapted to be supported on edge upon the rollers 26 in such a manner that during the swinging movement of the abrading wheel, the said wheel will engage the adjacent lower corners of the glass sheets and effect the rounding and finishing thereof.

The carriage 38, abrading wheel 43 and associated parts may be counter-balanced during swinging movement thereof if desired by means of a counter-weight 53 slidably received upon a rod 54 secured to said carriage at 54'.

In accordance with the present invention, the abrading wheel 43 is adapted to be simultaneously rotated during vertical swinging movement thereof. To this end, there is mounted upon the horizontal platform 55 carried by supporting framework 10 a second electric motor 56, the shaft 57 of which carries a sheave or pulley 58 about which may be trained one or a plurality of endless belts 59 also trained about a similar sheave 60 loosely mounted upon the adjacent end of shaft 37 which extends beyond bearing bracket 35. Fixed to the shaft 37 inwardly of sheave 60 is a relatively short arm 61 formed at its outer end with a horizontal bearing portion 62 within which is journaled a shaft 63. Mounted upon this shaft 63 is a sheave 64 about which is trained a plurality of endless belts 65 also trained about a second sheave 66 loosely received upon shaft 37 outwardly of sheave 60 but secured thereto. Also carried by shaft 63 is a second sheave 67 about which is trained a plurality of endless belts 68 also trained about a sheave 69 keyed to shaft 42. Upon operation of the motor shaft 57 to the shaft 42 and consequently to the abrading wheel 43 through the belt and sheave arrangement just described. More specifically, the sheaves 60 and 66 are driven from sheave 58, while sheaves 64 and 67 are driven from sheave 66, the sheave 69 being driven from sheave 67. Due to the particular construction and arrangement herein provided, the abrading wheel 43 can be rotated independently of and simultaneously with its vertical swinging movement.

The bearing sleeve 40 is normally maintained in a fixed position relative to the carriage 38 by means of the oppositely disposed machine bolts or the like 70 and 71 which pass through slots 72 in the carriage and engage the square central portion 41 of sleeve 40. In order to vary the position of the abrading wheel relative to the carriage, however, such as when it is desired to compensate for the wear thereof, there is provided an adjusting screw 73 which passes through the end plate 74 of carriage 38 and also engages the square portion 41 of sleeve 40. When it is desired to move the abrading wheel either inwardly or outwardly relative to the carriage, it is simply necessary to first loosen the bolts 70 and 71 and then rotate adjusting screw 73 in the proper direction, after which the said bolts 70 and 71 can again be tightened. Of course, upon any movement of the bearing sleeve 40 either inwardly or outwardly with respect to the carriage, it is also necessary to adjust the arm 61 rotatively upon shaft 37 so as to maintain the endless belts 68 taut. To this end, the arm 61 is shown as being secured to shaft 37 by fastening elements 75 and, upon loosening of these fastening elements, the arm 61 may be turned upon shaft 37 to either loosen or tighten the belts 68 depending upon whether the bearing sleeve is moved inwardly or outwardly.

In rounding and finishing the corners of glass sheets or plates with the machine above described, the said sheets 27 are first stood on edge in a vertical position upon the rollers 26, the lower horizontal edges of the sheets being received within the grooves 28 thereof, while the forward vertical edges are adapted to be received within the grooves 34 of the retaining member 33. The glass sheets are positioned so that the corners thereof to be rounded are disposed in the path of travel of the abrading wheel 40 43. The motor 46 is then placed in operation to rotate crank 49 and thereby effect a vertical swinging movement of the carriage 38 and abrading wheel 43 about the axis of shaft 37. The motor 56 is also operated to effect a simultaneous rotation of the abrading wheel. During the oscillating movement of the abrading wheel, the corners of the sheets to be rounded will be received within the grooves 44, and this swinging movement of the abrading wheel, coupled with the simultaneous rotation thereof, will effect the rounding and finishing of the corners of the glass sheets. The particular swinging movement of the abrading wheel relative to the corner to be rounded is, it is believed, clearly illustrated in Figs. 4, 5 and 6.

Although there has been described hereinabove and illustrated in Figs. 1 to 6, the rounding of corners of glass sheets the edges of which are disposed to form an angle of 90°, yet the present invention also contemplates the rounding of the corners of glass sheets the edges of which are disposed to form an angle other than a 90° angle. In other words, the present machine is adapted for rounding the corners of glass sheets the edges of which are disposed to form either an obtuse angle or an acute angle. Briefly stated, this may be accomplished by shortening or lengthening the arc through which the abrading wheel is swung. For instance, there is shown in Fig. 7 the rounding of the corner of a sheet of glass the edges A and B of which are disposed to form an acute angle, while in Fig. 8 is shown the rounding of the corner of a sheet of glass the edges C and D of which are disposed to form

an obtuse angle. When it is desired to round the corner of a sheet of glass the edges of which are disposed to form an acute angle, the arc through which the abrading wheel travels is 5 adapted to be lengthened, whereas when rounding the corner of a sheet of glass the edges of which are disposed to form an obtuse angle, the distance through which the abrading wheel travels is shortened.

10 In order to lengthen or shorten the arc through which the abrading wheel is swung, the apparatus illustrated in Figs. 7 and 8 may be provided. Thus, the crank carried by shaft 48 is here designated by the numeral 76, and the crank arm 51a (corresponding to crank arm 51 in Fig. 1) is formed of two separate parts 77 and 78, connected together end to end by a turnbuckle 79 so that, upon rotation of the turn-buckle, the parts 77 and 78 may be drawn either inwardly 20 toward one another to shorten the over-all length of the crank arm or moved further apart to increase the length thereof. The crank arm 51a is pivotally connected to the crank 76 by means of a bolt 80 which passes through a slot 25 81 in the said crank so that the throw of the crank as well as the length of the crank arm may be varied. When rounding the corners of glass sheets, the edges of which are disposed to form an obtuse angle as in Fig. 8, the throw of 30 the crank should be shortened as well as the length of the crank arm 51a.

It is to be understood that the form of the invention herewith shown and described is to be taken as the preferred embodiment of the 35 same, and that various changes in the shape, size and arrangement of parts may be resorted to without departing from the spirit of the invention or the scope of the subjoined claims.

I claim:

40 1. In a machine for grinding the corners of glass sheets, a movable abrading element, means for supporting the sheet to be ground on edge in a fixed substantially vertical position, means for swinging the abrading element vertically back and forth through an arc and in engagement 45 with the corner of the sheet to effect the grinding thereof and while the said sheet is maintained in such fixed position, and means for counterbalancing said abrading element.

50 2. In a machine for grinding the corners of glass sheets, an abrading wheel, a pivotally mounted bracket for supporting said wheel, means for supporting the sheet to be ground on edge in a fixed substantially vertical position, means for 55 swinging said bracket about its pivot to move the abrading wheel back and forth through a

substantially vertical arc and in engagement with the corner of the sheet to effect the grinding thereof and while the said sheet is maintained in such fixed position, said last mentioned means including a rotatable crank, and a crank arm pivotally connected at one end to said crank and at its opposite end to said bracket, means for rotating the abrading wheel during swinging movement thereof, and means carried by the bracket for counter-balancing said abrading wheel. 10

3. In a machine for grinding the corners of glass sheets, a supporting framework, a substantially horizontal supporting runway carried by said framework and adapted to support a plurality of sheets to be ground on edge in fixed substantially vertical position, said runway having a plurality of spaced grooves for receiving the lower edges of the said sheets therein, horizontally spaced bearing brackets carried by the framework, a horizontal shaft journaled in said bearing brackets, a swingable carriage keyed to said shaft, an abrading wheel carried by the carriage and having a plurality of peripheral grooves in substantial alignment with the grooves in said runway, means for swinging said carriage to move the abrading wheel bodily vertically through an arc in a plane parallel with the plane of the sheets and in engagement with the corners thereof, and means for rotating the abrading wheel. 20 25 30

4. In a machine for grinding the corners of glass sheets, a supporting framework, a series of substantially horizontally aligned rolls carried by said framework and adapted to support a plurality of sheets to be ground on edge in fixed substantially vertical position, said rolls having a plurality of spaced grooves for receiving the lower edges of the said sheets therein, means engaging the sheets for maintaining them in proper vertical position, horizontally spaced bearing brackets carried by the framework, a horizontal shaft journaled in said bearing brackets, a swingable carriage keyed to said shaft, an abrading wheel carried by the carriage and having a plurality of peripheral grooves in substantial alignment with the grooves in said rolls, means for swinging said carriage to move the abrading wheel bodily vertically through an arc 40 45 50 55 in a plane parallel with the plane of the sheets and in engagement with the corners thereof, means for rotating the abrading wheel, and means for counterbalancing said swingable carriage.

RAOUL J. LOUVIAUX. 55
